UNITED STATES PATENT OFFICE.

HERBERT WICKS, OF CLEVELAND, OHIO.

ELECTRIC IRON.

1,094,506.

Specification of Letters Patent.

Patented Apr. 28, 1914.

Application filed January 2, 1914. Serial No. 809,810.

To all whom it may concern:

Be it known that I, HERBERT WICKS, a citizen of the United States of America, residing at Cleveland, in the county of Cuyahoga and State of Ohio, have invented certain new and useful Improvements in Electric Irons; and I hereby declare the following to be a full, clear, and exact description of the invention, such as will enable others skilled in the art to which it pertains to make and use the same.

This invention relates to new and useful improvements in electric irons.

The object of my invention is to provide new and improved means for supporting the terminals of the heating coil so that the said terminals will not become heated when the iron is in use.

With this object in view my invention consists in certain new and improved features of construction and combination and arrangement of parts hereinafter described in the specifications, particularly pointed out in the claims and illustrated in the accompanying drawings.

In the accompanying drawings Figure 1 is a view in elevation of an iron embodying my invention. Fig. 2 is a section on line 2-2, Fig. 1. Fig. 3 is a section on line 3-3, Fig. 1. Fig. 4 is a section on line 4-4, Fig. 1. Fig. 5 is a section on line 5-5, Fig. 4.

The body of the iron comprises a base 10 which carries a post 11 having a screw threaded socket 12. Around the edge of the base is formed a seat 15. The heating element comprises a porcelain member 16 which has an opening 17 for the passage of the post 11, and on its upper surface is provided with a groove 19 and a double row of ribs 20. The heating wire shown at 22 is interlaced between the ribs 20 and the ends thereof are brought to the back or heel of the base. A layer of cement is placed on the member 16 over the wire 22. A cover 23 having a seat 25 in its top is arranged on the base over the heating element. On top of the cover 23 is mounted a U-shaped handle supporting member 26 comprising a bottom portion adapted to fit into the seat

25 and two upwardly extending standards which carry the grip piece 28. A screw 27 extends down through the bottom portion of the handle supporting member and through the cover 23 and is adapted to 55 screw into the socket 12 in the post 11.

To the rear standard of the handle supporting member of the iron at the heel of the iron is secured a bracket 29 and on this bracket are mounted two terminal forming 60 pins 30, and each pin is connected by a conductor 31 with one of the ends of the heating wire 22. The pins 30 are of the usual type for forming terminals on electric irons and are adapted to be received into the 65 usual type of plug (not shown) which carries the terminals of an electric circuit. By supporting the said pins from the handle of the iron it is possible to prevent the pins becoming heated as is now the case where the 70 said pins are mounted directly on the body of the iron. It is well known that when the pins become overheated they cause the wires connected to the plug to become brittle and when any strain is put on the wires they 75 readily break and also the overheating of the terminal pins causes a corroding of the pins which establish a resistance in the plug and prevents the electric current from heating the heating unit in the iron. On the 80 shell 23 is mounted a guard member 35, which extends around the lower portions of the pins 30 and serves to protect the conductors 31.

What I claim is:

1. An electric laundry iron comprising a body portion, an electric heating element arranged within said body portion and having the terminals thereof extending through said body portion, a standard mounted on said body portion, a bracket secured to said standard and spaced above said body portion, terminal pins carried by said bracket and means connecting the terminals of the heating element with said terminal pins on 95 said bracket.

2. An electric laundry iron comprising a base plate, a cover arranged on said base plate, an electric heating element arranged within said cover and having the terminals 100

thereof extending up through said cover, a handle supporting member mounted on said cover, a bracket secured to said handle supporting member and spaced above said cover, terminal pins carried by said bracket, and means connecting the terminals of the heating element with said terminal pins.

In testimony whereof, I sign the foregoing specification, in the presence of two witnesses.

HERBERT WICKS.
